UNITED STATES PATENT OFFICE.

HARRY J. RICHTER, OF WILMETTE, ILLINOIS, ASSIGNOR TO HORACE A. LESLIE,
TRUSTEE, OF CHICAGO, ILLINOIS.

STEAM-TURBINE BLADES.

1,062,737.

Specification of Letters Patent.

Patented May 27, 1913.

Application filed August 3, 1908. Serial No. 446,551.

To all whom it may concern:

Be it known that I, HARRY J. RICHTER, a citizen of the United States, and a resident of Wilmette, Cook county, Illinois, have invented certain new and useful Improvements in Steam-Turbine Blades and Methods of Assembling and Securing Them in Turbine Elements, of which the following is a full, true, clear, and exact description.

- 10 My invention relates to improvements in steam turbines and has special reference to improvements in the form, construction and assemblage of the blades upon both rotor and stator.
- 15 The object of my invention is to materially reduce the cost of steam turbines and especially to reduce the labor and time expended in assembling and securing the blades upon the members of a turbine.
- 20 Special objects of my invention will appear hereinafter.

My invention consists broadly in a new article of manufacture, comprising a plurality or series of turbine blades, spaced apart, and 25 fastened together at their bases in such manner that a common base is provided therefor, said base being formed to fit the blade groove of a turbine rotor or stator and said base being sufficiently malleable or flexible to be 30 readily conformed to the curve of such groove.

My invention further consists in a new article of manufacture, comprising a plurality or series of turbine blades, suitably 35 spaced apart at their bases, and a rod, bolt or rivet piercing the bases of said blades and securing them together as one piece for ready insertion in the groove of a turbine rotor or stator.

40 My invention also involves the end to end interlocking of such sections in the groove of the turbine member or element. And further my invention consists in various details of construction and in combinations of parts, 45 all as hereinafter described and more particularly pointed out in the claim.

My invention will be more readily understood by reference to the accompanying drawings, forming a part of this specification and in which:

Figure 1 discloses my invention as applied to the side of a turbine rotor or a stator; Fig. 2 discloses the invention as applied to the periphery of a rotor or a stator; 55 Fig. 3 is an enlarged sectional view on the line X--X of Fig. 1; Fig. 4 is an enlarged section on the line Y--Y of Fig. 2; Fig. 5 is a perspective view illustrative of the component parts of my novel blade section or multiple. Fig. 6 illustrates the manner of 60 assembling a blade section; Fig. 7 shows a complete blade section; Fig. 8 is a side view thereof as the section appears before the base thereof is planed or milled; and Fig. 9 is a similar view of the complete section ready to 65 be assembled with others in a turbine rotor or stator.

In the drawings, 2, represents a portion of a turbine rotor (or a turbine stator), having a plurality of concentric grooves, 3, 70 to receive as many annuli of blades. A portion of one such annulus of blades is shown in Fig. 1. In Fig. 2 I have shown a rotor or stator, 4, of a different type, this being provided with one or more peripheral grooves, 75 5, in which the blades are arranged.

My novel article of manufacture, to wit, the blade section or blade multiple is adapted for attachment to or assemblage with all kinds of turbine members, irrespective of 80 type. I make these blade sections or multiples in relatively short lengths and bend them to fit the curve of the groove in the turbine member to which they are applied. Many sections are required to make up a 85 blade annulus in a large turbine, the number varying with the circumferential length of the groove in which they are placed.

Each blade section or multiple, A, as herein shown, is made up of a plurality of 90 blades, a, a plurality of spacers, a', and a rod, bolt or rivet, a''. I desire that it shall be understood that my blade section, without departing from the spirit of the invention, may be an integral structure to the extent that the spacers, a', and the blades, a, 95 may be formed integrally and secured by the rod or rivet, a'', but I prefer to form the sections of the numerous parts shown in the drawings.

The form or configuration of the blades is determined by the type or design of the turbine of which they are to form a part and the spacers take their form from the blades. I preferably make the blades from 105 rolled steel by simply cutting up bars of the desired cross sections. The base portion of each blade is provided with a hole, a³, and each spacer has a corresponding hole, a⁴. The spacer which is to form the end 110

of the section is provided with a counter-sink or recess, a^5 . Such parts having been prepared I place them in a vise or assembling jig of substantially the form shown in Fig. 6, first stringing the blades and spacers upon the rod or rivet, a^2 . The jig comprises the heads or members, B, B', connected by the parts b^1 , b^2 , which latter are separated by a groove b^3 . The part B contains an opening C^3 , through which the end of the rod or rivet, a^2 , may be reached with a riveting tool, C. At the time that the spacers and the blades are assembled in the jig these parts are of substantially the same width, the base portions not having then been planed or finished as hereinafter described. The member, B', contains a screw, B'', and a gib, b^4 , and after assembling the parts in the groove of the jig I drive this screw and gib against the head, a^6 , of the long rivet, a^2 . In this manner I force the rivet forward and jam the blades and spacers together against the jaw, B. The end of the rivet is thus caused to project through the last spacer and while in this condition it is peaned or riveted to form the head, a^6 , in the recess, a^5 . The blades and spacers are in this way firmly and permanently united to form a rough blade section or unit. When this has been accomplished I remove the rough section from the vise or jig and placing the same in a suitable machine plane or mill the base on both sides to form the smooth sides, a^8 . The width of the base portion of the section is thus reduced to the width of the groove in the rotor or stator, which is to receive the same. The relative width of the blades and of the base portion appears in Fig. 7. As shown in Fig. 6 the recess in the end spacer of the section is of greater depth than the head, a^6 , of the rivet; and the cavity remaining is large enough to receive the rivet head, a^7 , of another blade section, in abutment therewith. In placing these blade sections in a turbine member I first tap or force one end of a section into the groove thereof, and then by means of a suitable tool calk or pean the metal over or against the base of the section, as shown at 5'5' in Figs. 3 and 4. Having secured one end of the section in this manner I proceed to drive the remainder of the section into the groove, using an ordinary mallet for the purpose. Light blows upon the ends of the

blades are sufficient to force the section into the groove and cause it to conform to the curve of the groove; and thus the originally straight section is readily converted into a curved section in the receiving groove. 60 The calking of the section from end to end is usually completed after the section has been set or planted in the groove, in the manner described, and it will be obvious that the calked or battered edges of the 65 metal admirably serve the purpose of fastening and locking the blades in the turbine member. In the manner described section after section is placed in the groove of the member, the end of each section being 70 interlocked with the end of the preceding section, until the ring or annulus of blades is completed. Both Fig. 1 and Fig. 2 show two blade sections as they appear after being planted in the groove and one section as 75 it appears when being set or planted therein.

It is obvious that the section or unit herein described is capable of ready modification to suit turbine members of various forms, and that the base portion of the section may 80 be varied in cross section to suit other methods or means of calking or fastening them.

As these and other modifications will readily suggest themselves to one skilled in 85 the art, I do not confine or limit my invention to the specific structures herein described.

Having thus described my invention I claim as new and desire to secure by Let- 90 ters Patent:

A new article of manufacture comprising a plurality of turbine blades and spacers and a rivet passing through said blades and spacers and headed at both ends, the head 95 of the rivet being exposed at one end of the section thus formed, the other end of said section being provided with a recess and the common base formed by said spacers and the ends of the blades being of less 100 width than the free ends of said blades, substantially as described.

In testimony whereof, I have hereunto set my hand, this 31st day of July, 1908, in the presence of two subscribing witnesses. 105

HARRY J. RICHTER.
